(57) **CLAIM**

The ornamental design for a pot as shown and described.

DESCRIPTION

FIG. 1 is a top perspective view of a pot showing our new design;

FIG. 2 is a bottom perspective view thereof;

FIG. 3 is a front elevational view thereof;

FIG. 4 is a back elevational view thereof;

FIG. 5 is a right side elevational view thereof;

FIG. 6 is a left side elevational view thereof;

FIG. 7 is a top view thereof; and,

FIG. 8 is a bottom view thereof.

The broken lines are shown for the purposes of illustrating parts of the article that form no part of the claimed design.

1 Claim, 4 Drawing Sheets
